UNITED STATES PATENT OFFICE

2,375,303

LATHING

Carl A. Karelius, Altadena, Calif.

Application July 6, 1943, Serial No. 493,644

2 Claims. (Cl. 72—116)

This invention relates generally to lathing of the type embodied in my U. S. Patent No. 2,236,141, issued March 25, 1941, and in my co-pending application for U. S. patent, Serial No. 488,151, filed May 24, 1943, in both of which is disclosed, a plaster foundation including a backing sheet combined with front and rear reinforcing wires in intersecting relation on opposite sides of the backing sheet and co-acting with plaster keying openings in the latter at the wire intersections, to lock the plaster to the wires.

An object of the present invention is to provide a lathing of the above described general character whose backing sheet is preformed structurally to present a cross sectional contour or profile such as to render the sheet free to be readily flexed under normal troweling pressure, a considerable amount away from the front wires of parallel rows lying between points of nailing of the lathing to studs, beams, or other supports, which nailing restricts the amount to which the backing sheet could otherwise be flexed away from such front wires without excessive troweling pressure and the attending waste of mortar forced in excessive quantity through the plaster keying openings in an effort to embed the said front wires in the plaster as much as possible, whereby to insure an increased thickness of plaster between such front wires and the backing sheet in response to normal troweling pressure, so as to obtain a bond of maximum strength between the front wires and the plaster, with an economical use of plaster and by the usual plaster applying technique practiced by the plasterer.

In its more specific aspect, the invention provides a preformed backing sheet combined with the reinforcing wires as above described, by grooving, channeling, or ribbing the sheet at locations directly behind the parallel rows of front wires so as to normally space the backing sheet from such wires and provide the excess of backing sheet material to insure the deep embedding of the wires in the plaster with the aforesigned advantages, as well as tend to increase the strength of the backing sheet as a unit against excessive bowing under troweling pressure and sagging under the weight of moist plaster.

A further object of this invention is to provide lathing whose construction and functional relationship of elements as above described enables a more uniform strength of the plaster coating throughout the area of the plaster mass, to be obtained by balancing the added plaster thickness at the plaster keying openings of the backing sheet, with an added thickness at the inter-

mediate front wires by increased flexing of the backing sheet at the latter and consequent deeper embedding of such wires in the plaster coating.

With these and other objects in view, the invention resides in the combinations, arrangements and functional relationships of elements as set forth in the following specification and particularly pointed out in the appended claims.

In the accompanying drawing,

Figure 1 is a view of the lathing embodying this invention in front elevation, and shown applied to building frame members;

Figure 2 is a fragmentary view of the lathing in rear elevation as applied in Figure 1;

Figure 3 is a sectional view at an enlarged scale, taken on the line 3—3 of Figure 1, and with plaster applied to the lathing;

Figure 4 is an enlarged sectional view taken on the line 4—4 of Figure 1 and showing the lathing prior to the application of plaster thereto;

Figure 5 is a view similar to Figure 4 showing the lathing after plaster has been applied thereto.

Referring specifically to the drawing, this invention comprises a backing sheet 10 which is preferably made of a relatively thin, strong, absorbent paper or equivalent material having openings 11 arranged in parallel rows longitudinally and transversely of the sheet, with the openings being elongated in one and the same direction such as longitudinally of the sheet and being so spaced as to leave a relatively small web 12 between the ends of adjacent openings so as to weaken the sheet at such points for greater flexibility of the sheet therat. Furthermore, the edges of the openings 11 are rounded or beveled towards the back side of the sheet as indicated at 13 so as to squeeze or constrict mortar forced through the openings, and thus densify the mortar.

The backing sheet is preformed by heavy pressure with or without heat and/or moisture, to define grooves 14 on the front side of the sheet, with the lengths of the grooves extending in parallelism to the longitudinal rows of openings 11, and with the grooves arranged medially between adjacent longitudinal rows of the openings, for co-action with certain reinforcing wires with which the sheet is combined in a manner to be later described. It will be understood that the term "grooves" is to be broadly interpreted to include any lateral deforming or offsetting of the backing sheet 10 by which the functional equivalent of preferably continuous depressions or grooves in the front surface of the sheet is obtained, and which depressions serve to normally

space such portions of the sheet away from certain reinforcing wires and to render the sheet free to be flexed in one direction such as transversely between fixed points of anchorage of the lathing to a stud, beam, or other support *S* as will be later fully described.

On the front side of the backing sheet are front wires *15* and *16*, the wires *15* spanning the openings *11* transversely of the latter and medially between the ends of the openings. The wires *16* intersect the wires *15* at a right angle thereto so as to extend parallel to the length of the openings *11* and medially between the longitudinal rows thereof directly in front of the portion of the backing sheet having the grooves *14*, to thus normally space such portion of the sheet a considerable amount rearwardly from the wires *16*. The wires *15* and *16* are welded or otherwise secured together at their points of intersection as indicated at *17* so as to rigidly and permanently connect these wires.

On the back side of the backing sheet *10* are rear wires *18* disposed intermediate and parallel to the front wires *16* so as to interpose the sheet therebetween. The rear wires *18* span the openings *11* longitudinally of the latter and are welded or otherwise permanently secured to the other front wires *15* at the points of intersection of the latter and the rear wires in the openings *11* as indicated at *19*.

In wood frame construction, for example, sheets of the lathing are secured preferably at the rear wires *18* by fastening members such as nails or staples *25* to the supports *S*, and at a sufficient number of locations on the lathing sheets to securely hold same in place.

By virtue of the preformed grooves *14* in the backing sheet of the lathing, additional backing sheet material is provided between any two points of rigid anchorage of the lathing to the support *S* by the fastening members *25*, so that upon applying mortar to the lathing under normal troweling pressure, the backing sheet will yield readily away from the front wires *16* by flattening out or at least reducing the depth of the grooves *14*, thus enabling a greater proportion of the mortar to flow behind the wires *16* to more deeply embed the latter in plaster for a stronger bond between the plaster and the lathing.

It is thus unnecessary for the plasterer to exert any excessive troweling pressure against the backing sheet in an effort to embed the front wires *16* deeper into the plaster by stretching the backing sheet away from these wires between points of anchorage of the lathing to the supports *S*, as the usual plastering technique can be followed for maximum speed and efficiency. It will also be noted that the grooves *14* provide added backing sheet material between such grooves and the long sides of adjacent openings *11*, so that the backing sheet will readily flex

away from the other front wires *15* to a greater extent than previously possible, so as to also more deeply embed the overlying portions of the wires *15* in plaster to add to the strength of the bond between the plaster and wires.

Furthermore, the forming of the backing sheet to provide the grooves *14*, materially strengthens the backing sheet so as to tend to produce bowing of the sheet longitudinally under troweling pressure and sagging of the sheet under the weight of moist plaster. Also the added amount of plaster resulting from the provision of the grooves *14* compensates for the added thickness of plaster through the openings *11* so that a more uniform overall thickness and hence strength of the finished slab is obtained in order for it to be more rigid and more adequately resist fracture under service conditions.

I claim:

1. Lathing comprising: a flexible backing sheet having openings arranged in rows; intersecting rows of front wires on the front of said sheet secured together at their intersections, with the wires of one row spanning said openings; and rear wires on the back of said sheet spanning said openings in intersecting relation to the wires of said one row and secured to the latter at such intersections in said openings; said backing sheet being grooved along the length of and behind the front wires of the other row thereof to provide excess backing sheet material between spaced points of rigid anchorage of the lathing to a support, so as to enable the sheet to be readily flexed away from the front wires of said other row under normal troweling pressure of mortar against the backing sheet, whereby such front wires will become deeply embedded in plaster.

2. Lathing comprising: a flexible backing sheet having elongated openings arranged in rows in longitudinal and transverse directions; intersecting rows of front wires on the front of said sheet, secured together at their intersections, with the wires of one row spanning said openings transversely of the lengths of the latter; and rear wires on the back of said sheet spanning said openings longitudinally of the latter and secured to the intersecting front wires in said openings; said backing sheet having grooves in its front surface extending longitudinally of and behind the front wires of said other row thereof, so as to provide an excess of backing sheet material rendering the backing sheet capable of being readily flexed away from the both rows of front wires under normal troweling pressure of mortar against the backing sheet, whereby the front wires will become deeply embedded in plaster to provide a bond of maximum strength between the plaster and front wires.

CARL A. KARELIUS.
